UNITED STATES PATENT OFFICE.

ALEXANDER BERNHARD DRÄGER, OF LUBECK, GERMANY, ELFRIEDE DRÄGER, NÉE STANGE, EXECUTRIX OF SAID DRÄGER, DECEASED.

RESPIRATORY HEADGEAR.

Application filed June 11, 1926, Serial No. 115,171, and in Germany June 29, 1925.

In respiratory apparatus, in which breathing is done through a mouth-piece, it is essential, especially for life saving work in mines, that the parts of the mouth-piece should be so attached to the head of the wearer, that in spite of sharp pulls or such hasty movements, which experience has shown often occur in connection with life-saving work underground, said portions of the mouth-piece cannot be pulled out of the mouth or at least cannot be so displaced, that the danger arises of the wearer breathing in noxious gases or external air. It will readily be apparent, that the correct solution of this problem determines the practical value of the respiratory apparatus or is at least of a nature to materially influence it. It has already been proposed to effect a secure attachment of the parts which serve for breathing through the mouth-piece, by connecting them with a cap or head-piece. The present invention has the same object but involves new means, which will provide that the head-piece for its own part shall rest firmly and securely on the wearer's head, whilst at the same time it shall form an effective protection to the skull of the wearer against external injuries such, for example, as might be caused by falling stones, blows or unexpected impacts. The means, according to the invention, for realizing these objects comprises chiefly a guard-plate provided within the head-piece and preferably crown-shaped of leather or other suitable material.

The straps by which the mouth-piece is attached may be passed over the guard plate, if the latter is crown-shaped. This will be particularly preferred if instead of a simple mouth-piece a mask is used, or the straps may be detachably or firmly secured to the guard-plate itself.

In connection with the invention other features may be made use of as will be well understood from the description given below.

The accompanying drawings show various constructional examples of the invention.

Fig. 1 is a front elevation of a person's head showing the mouth-piece of a respiratory apparatus in position with the head-piece in section.

Fig. 2 is a reduced lateral elevation of Fig. 1 on a reduced scale.

Figs. 3 and 4 show the upper part of the wearer's head in front elevation, the head piece in position thereon being in section.

Fig. 5 is a plan of the wearer's head, the external cap and the inner protective plate being omitted in order to show the ring-shaped bearing surface of the protective plate.

Fig. 6 is a vertical section of a modification in which the mouth-piece is replaced by a mask.

Fig. 7 is a lateral elevation of a detached cap to a reduced scale.

Fig. 8 is a lateral elevation of the guard plate connected with a mask adapted to be used together with the cap shown in Fig. 6.

Fig. 9 is a plan of Fig. 8.

Fig. 10 a section of the guard plate shown in Figs. 8 and 9.

Fig. 11 is a cap provided with a modified guard plate.

Fig. 12 is a cross section of said cap, and

Fig. 13 a section drawn to the line 13—13 of Fig. 12 to a somewhat larger scale.

According to Figs. 1 and 2 the mouth-piece *a* placed partly in the wearer's mouth together with its pertinent parts, such as the nose-clip *b*, saliva trap *c* and breathing tubes *d* and *e*, is attached to the head-piece *h* by means of the straps *f* and *g*. Inside the cap *h* the protective plate *i*, which for example may be made of leather is so adjusted, that it will bear directly upon the wearer's head (Fig. 1). The attachment or fastening of the plate *i* is effected preferably by attaching it to the external crown of the cap *h* (Fig. 1) by means of light rivets *m*, or by sewing or gluing it into the crown with a suitable adhesive. The external shape of the cap *h* thus is somewhat modified.

The upper crown of the cap *h* in order to prevent bending is preferably also made of a resistant or stiff material or is combined with some other material. The protective plate *i* is preferably provided with an annular surface *n* (Figs. 1 and 5) to act as a bearing surface, which is formed by reason of the fact that the central surface *o* (Fig. 1) of the protective plate is domed towards the top. This not only has no prejudicial effect upon the tight fit of the head-piece, which is then secured solely by means of the annular bearing surface *n* adapting itself to the top of the skull, but the advantage is also obtained, that the wearer's head is left ex-

95

100

105

110

posed in the centre, and in this way there is provided a layer of air between the plate *l* and the head. The annular flat surface *n* need not be arranged at the utmost edge 5 of the protective-plate, but may be disposed at a greater or less distance from such edge, as is shown in Fig. 10. A circulation of this air can be secured by means of small holes 1 and 2 provided in the cap *h* and the plate *i* respectively (Figs. 6 to 8). In order to ensure a still more comfortable fit of the protective-plate *i* the latter can be lined or padded upon the side facing the head. In Fig. 4 a padding or lining is shown fastened 10 in the form of a ring-shaped roll *p*, in a protective-plate *i* that is not domed. In this construction the lining simultaneously fulfills the duties of the annular bearing surface *n*, and of the dome *o* shown in Fig. 1, because the roll *p* creates an intermediate space 15 between the centre of the plate and the head of the wearer. It is however also possible, and occasionally preferable, to provide the edge-surface of the protective plate shown 20 in Fig. 1 with a lining.

The above described straps instead of being attached to the head piece *h* may be attached to the protective-plate itself, as is shown in Fig. 6.

30 In the modification shown in Figs. 6 and 7 it is assumed that instead of the mouth-piece, a mask *a'* is used provided with an inner auxiliary mask *a''*, which is connected with a breathing tube *d'* in known manner. 35 For holding the mask *a'* head straps *g'* are used, Figs. 6, 7 and 8, which are attached to the upper side-corners of the mask, and are passed through loops 6 to be connected with one another at 5 (Fig. 9) and finally attached to the centre of the upper rim of the mask. The loops 6 are preferably formed by a metal holder attached at the end of the skull strap 7, which itself is attached to a special pull plate 3 by a buckle 4. The pull 40 plate is moreover connected to the upper part of the mask on both sides by two temple straps 10, and is moreover provided with two loops 11 at its lower end, through which passes a strap 12, which with its ends is connected at 13 with the lower part of the mask. All these head straps pass over the protection plate *i*, and thus hold the protective plate *i* and also the mask securely to the head.

55 The said straps may be attached to the guard plate for instance by a special cross strap 18 firmly attached at one end to the guard plate and passed through a loop 17 fastened to the guard plate. The strap 18 60 crosses the pull plate 3 and may be buttoned to a button 19 secured to the protective plate *i*. The pull plate 3 being wedge-shaped at this end prevents sliding movements of the harness on the protective plate *i*. 65 The straps *g'*, 10 and 12 may be made

yielding by the insertion of intermediate elastic pieces 7 as shown in Figs. 6 and 7. It is evident that by the construction described all inconvenient pressure by the loops, buckles and the like are avoided.

The cap of pliable material may be similarly shaped as that described with reference to Figs. 1 to 5. In the construction shown in Figs. 6 and 7 the width of the cap is made adjustable by a strap provided with a buckle 21. The connection of the protection plate *i* with the cap may be detachable. In the construction shown the connection is secured by a locking member or catch 23, which is rotatably attached to discs 25 on the protective plate *i* and passes through a reinforced slot 24 in the cap, and after passing through the slot is turned for 90° through locking the cap to the protective plate. The disc 25 attached to the protective plate *i* serves also as a guide for the skull strap 7 at both sides.

A guard plate *i* may also be used for the forehead, in which case preferably a number of small guard-plates *i'* may be attached inside the cap *h* as shown in Figs. 10, 11 and 12. Such forehead guard plates may, if so desired be provided with ribs 6, and may also be made of leather or similar material.

I claim:—

1. In a gas mask having a respiratory device, a harness consisting of a plurality of straps adapted to extend across and bear upon the wearer's head to support the respiratory device in operative position, a protective plate inserted between the head and said harness and adapted to bear upon the skull along an annular line without touching the area enclosed by said annular line, and a cap enclosing said plate and detachably attached thereto.

2. The combination set forth in claim 1, in which the straps are connected with each other and with the protective plate by means of buckles arranged in such a manner as to bear upon said protective plate.

3. In a gas mask having a respiratory device, a harness consisting of a plurality of straps adapted to extend across and bear upon the wearer's head to support the respiratory device in contact with the face, a protective plate inserted between the head and said harness and adapted to bear upon the skull along an annular line without touching the area enclosed by said line, and a strap detachably attached to said plate and passing across the straps of said harness to form a detachable connection between the harness and the protective plate to prevent relative displacement thereof.

4. In a gas mask having a respiratory device, a head piece comprising a protective plate adapted to bear upon the skull along an annular line without touching the area enclosed by said annular line, a locking mem-

ber pivoted to said plate, a cap enclosing said plate and provided with a slot adapted to receive said locking member, whereby the cap may be secured to said plate by the locking member, and a harness having portions extending within said cap and bearing upon said plate, said harness being adapted to support the respiratory device in operative position.

10 5. In a gas mask having a respiratory device, a head piece comprising a protective member so shaped as to bear upon the skull along an annular line without touching the area enclosed by said annular line, a cap enclosing said protective member and detachably attached thereto, a plurality of forehead guard plates attached to said cap, and supporting connections carrying the

respiratory device and bearing on said protective member.

6. In a gas mask having a respiratory device, a head piece comprising a cap of pliable material adapted to be fitted to the head in the conventional manner so as to touch the head along a peripheral line, a plurality of forehead guard plates attached to said cap, a resistant protective plate enclosed by and detachably attached to said cap and so shaped as to bear upon the skull along an annular line situated above said peripheral line, and supporting straps carrying the respiratory device and extending across and bearing upon said protective plate.

In testimony whereof I have signed my name to this specification.

ALEXANDER BERNHARD DRAGER.
